(57) **CLAIM**

The ornamental design for an apparatus for mounting a controller to a user, as shown and described.

DESCRIPTION

FIG. 1 is a perspective view of a first embodiment of an apparatus for mounting a controller to a user, and in particular, to the left foot of the user;

FIG. 2 is a top plan view of the new design of FIG. 1;

FIG. 3 is a bottom plan view of the new design of FIG. 1;

FIG. 4 is a first side elevation view of the new design of FIG. 1;

FIG. 5 is a second side elevation view of the new design of FIG. 1;

FIG. 6 is a front elevation view of the new design of FIG. 1;

FIG. 7 is a rear elevation view of the new design of FIG. 1; FIG. 8 is a perspective view of a second embodiment of an apparatus for mounting a controller to a user, and in particular, to the right foot of the user;

FIG. 9 is a top plan view of the new design of FIG. 8;

FIG. 10 is a bottom plan view of the new design of FIG. 8;

FIG. 11 is a first side elevation view of the new design of FIG. 8;

FIG. 12 is a second side elevation view of the new design of FIG. 8;

FIG. 13 is a front elevation view of the new design of FIG. 8; and,

FIG. 14 is a rear elevation view of the new design of FIG. 8.
